UNITED STATES PATENT OFFICE

158,343

HAIR WAVING CLAMP

Stanley C. Watson, St. Paul, Minn., assignor to
Raymond Laboratories, Inc., St. Paul, Minn., a
corporation of Minnesota

Application January 4, 1949, Serial No. 60

Term of patent 14 years

(Cl. D86—10)

To all whom it may concern:

Be it known that I, Stanley C. Watson, a citizen of the United States, residing at St. Paul, in the county of Ramsey and State of Minnesota, have invented a new, original, and ornamental Design for a Hair Waving Clamp, of which the following is a specification, reference being had to the accompanying drawings, forming a part thereof.

In the drawings:

Fig. 1 is a perspective view of a hair waving clamp showing my new design;

Fig. 2 is a side elevational view; and

Fig. 3 is an end elevational view.

I claim:

The ornamental design for a hair waving clamp, as shown.

STANLEY C. WATSON.
